LAPPING MACHINE

Filed March 31, 1932

2 Sheets-Sheet 1

FIG-1: A top-down view of the assembly showing a central vertical axis with various components labeled 1 through 17.

FIG-2: A cross-sectional view showing internal parts labeled 1 through 17. It includes a central vertical axis with a valve-like component (labeled 10, 11, 12, 13, 14, 15, 16, 17) and a base structure with a central bore.

FIG-3: A side view of the assembly, showing a vertical cylindrical body with a flared base and a central vertical axis.

FIG-4: An exploded view showing the assembly disassembled into various parts. Labels include 1, 2, 4, 5, 6, 7, 8, 9, 10, 11, 12, 13, 14, 15, 16, 17, 18, 19, 20, 21, and 22.

FIG-5: Another cross-sectional view, similar to FIG-2, showing the internal structure of the assembly.

UNITED STATES PATENT OFFICE

OTTO R. RELLER AND CLARENCE W. HALLENE, OF MOLINE, ILLINOIS, ASSIGNEES TO
MOLINE TOOL COMPANY, OF MOLINE, ILLINOIS

LAPPING MACHINE

Application filed March 31, 1932. Serial No. 602,166.

Our invention has reference to an improvement in lapping machines, and relates more specially to the lapping tool or head, and means for increasing the efficiency thereof. 5 It also relates more particularly to the type of tool set forth in Letters Patent of the United States No. 1,761,126, issued to Wilson P. Hunt et al June 30, 1930. Said patent shows a structure including a cylindrical 10 body supporting a plurality of grinding stones and a central expansion element of double cone formation. This element is permitted a limited amount of freedom in the cylinder, making it possible to move in any 15 direction, or "float" during the operation of the tool, enabling the stones to conform instantly to irregularities or inequalities in the bore of the cylinder or other part that is being honed. On account of the cones being 20 of circular formation a shifting of the expansion element in one direction or the other tends to reduce the space between the stone controlling devices at the sides thereof, so that there is a failure of the stones to 25 form their work properly. The chief purpose of the present invention is to remedy this defect, and provide means for keeping the stones up to their work at all times.

The particular construction, arrangement, 30 and mode of operation of the parts of the invention will more fully appear from the following specification, taken in connection with the accompanying drawings, in which;

35 Fig. 1 is a vertical medial section of a lapping head embodying the invention, with some parts shown in full lines.

Fig. 2 is a cross-section on the broken line 2—2 of Fig. 1.

40 Fig. 3 is an enlarged detail of the expansion element 12.

Fig. 4 is a diagrammatical view, in cross-section, showing the faulty manner of operation.

45 Fig. 5 is a similar view, showing the improved method of operation.

Fig. 6 is an enlarged view, similar to Fig. 1, showing a modified form of the invention.

50 Fig. 7 is a cross-section on the line 7—7 of

The figures of the drawings are fragmentary, and limited to the lapping tool or head, it being understood that the parts disclosed are supported and operated by other mechanisms in a manner well known for such instrumentalities. 55

In Fig. 1 the reference number 1 indicates the lower part of a tubular support, carrying a head 2, containing channels 3, in which are movably held shoes 4, for the support of lapping stones 5. The shoes 4 are encircled at their ends by coiled springs 6 and 7, also known in the art, and tending to hold the shoes yieldably in the channels 3. Near the ends of said shoes pins 8 are fixed thereto and projected inwardly through bearings 9 in the support 1, and into engagement at their inner ends with expansion members 10 and 11 on the ends of a core 12, in the bore of the support 1. Said expansion members are of a frusto-pyramid formation, in inverted position, and there is a clearance between the circular heads 13 of said members and the walls of said bore, as shown in said former patent, permitting a limited movement of the expansion element independently of the support. Downward movement of the core 12 may be effected by means of a rod 14 projected upwardly through the tube 1, and the lower end of which rod bears against a ball 15 in a bearing in the upper end of said core. As a result of such downward movement the pins 8 and shoes 4 are moved outwardly coextensively, adapting the stones to the work in which the tool is operating. The rod 14 can be actuated in any suitable manner, such as that shown in said former patent. 75 80 85

The expansion members 10 and 11 are rectangular in cross-section as shown herein, although variations in the shape thereof may be had. It will be observed that the ends of the pins 8 are in contact with the faces of said members, and that the position of the expansion member can be shifted to one side or the other without changing the relative positions of the pins above and below the same. For example, in Fig. 4, which is the form in which a conical expanding member is used, a set of stones 18 is shown, held by shoes 19, fitted with pairs of pins 20 and 21, the inner 90 95 100

ends of which bear against a conical member 22. The cone is shown moved to one side of the center line of the figure, with the stones 20 moved in the same direction, bringing the ends of the pins 21 on a smaller circumference of the cone, and permitting the pins to approach each other. This results in a reduction of the spacing of the pins 21, and as a consequence the desired amount of contact between the stones controlled by said pins and the wall of the cylinder is not maintained, to the detriment of the work.

In said Figure 4 the amount of variation in the parts is exaggerated somewhat, for the purpose of the illustration, but occasionally a very slight variation, such as the thousandth of an inch will be attended with unsatisfactory results.

The operation of the parts as carried out in the present invention is indicated in Fig. 5, in which the expanding element 11 is again shown moved to the left of the center line, but with the upper and lower pins in contact with the flat faces of said element, and the spacing of said pins maintained. The only variation in this spacing will come about through the change in the position of the element 11 longitudinally, with a portion thereof of different diameter separating the pins.

It will be understood that in the operation of the tool all of the parts rotate in unison, and that as shown in Fig. 5 the pair of stones at the sides, and those at the top and bottom alternate with each other in position in quick succession. The same is true of the pins 8, but whatever position said pins may be in the spacing of such pins will at all times equal the thickness of the section of the part 11 or part 10 which separates them, and gauges the distance between them.

In Fig. 6 is shown the lower end of a tubular support 24, in the center of which is a cylinder-shaped expansion member, 25, also capable of a limited amount of play in the bore of said support. In the sides of said expansion member are recesses 26 and 27, to receive the inner ends of sets of pins 28 and 29, with which are connected shoes 30, carrying stones 31, which shoes and stones are movable in channels 32 and the head 33. The ends of the shoes 30 are held for yieldable movement outwardly by coiled springs 34. The recesses 26 and 27 are formed with walls 35 and 36 inclined upwardly and outwardly, against which the ends of the pins 28 and 29 engage, the downward movement of the expansion element, in a manner similar to that of the part 12, operating to move the pins outwardly and increase the circumference of the movement of the stones. The width of the recesses 25 and 26 is somewhat greater than the thickness of the pins 28 and 29, permitting independent movement of the expansion element to one side or the other, similar to that shown in Fig. 5. One advantage to be found in

the structure shown in Fig. 6 is in the reinforcement given to the sides of the expansion member, with little likelihood of breakage thereof. The results to be secured therefrom are substantially the same as in the former case.

What we claim and desire to secure by Letters Patent, is:

1. In a lapping machine, a tubular support for honing elements, an expansion element held in said support so as to have a limited clearance therefrom, and provided on its sides with plane surfaces, shoes carried by said support, connections between said shoes and said expansion element bearing against said planes, and means for actuating said expansion element.

2. In a lapping machine, a tubular support for honing elements, an expansion element held in said support so as to have a limited amount of clearance therefrom and provided on its sides with oppositely disposed plane surfaces, stone bearing shoes carried by said support, and pairs of radial pins held slidably in said support, connected at their outer ends with said shoes and bearing against said plane surfaces at their inner ends.

3. In a lapping machine, a tubular support for honing elements, an expansion element held in the bore of said support so as to have clearance with the walls of said bore, and including a pair of frusto-pyramidal members having flat faces in rectangular formation, shoes carried by said support, means for holding said shoes yieldably in inner positions, and pairs of radial pins connecting said shoes with said members and bearing against the flat surfaces thereon.

4. In a lapping machine a tubular support for honing elements, an expansion element held in the bore of said support and having clearance therefrom, and of double wedge formation, stone-carrying shoes carried by said support, pairs of radial pins slideable in said support, connected with said stone-carrying shoes at their outer ends and in contact at their inner ends with said expansion element, and means for adjustment of the position of said expansion element to spread said shoes, the lateral shifting of said expansion element being possible without disturbing the relative positions of the pins bearing against the sides thereof.

5. In a lapping machine a tubular support, a cylinder-shaped expansion element in the bore of said support having clearance from the walls of said bore, and provided with sets of recesses with inner cam faces, stone-holding shoes carried by said support, and radial pins held slidably in said support, fixed at their outer ends to said shoes and projected into said recesses at their inner ends.

6. In a lapping machine, a tubular sup-

port, a cylinder-shaped expansion element in the bore of said support having clearance from the walls of said bore, and provided with sets of recesses with inner cam faces, 5 stone-holding shoes carried by said support, and radial pins held slidably in said support, fixed at their outer ends to said shoes and projected at their inner ends into said recesses, said pins having a limited lateral play in the recesses.

10 In testimony whereof, I affix my signature.

OTTO R. RELLER.

CLARENCE W. HALLENE.
